UNITED STATES PATENT OFFICE.

THOMAS E. CARR, OF PROVIDENCE, RHODE ISLAND.

TRAIN STOP.

Application filed April 12, 1922. Serial No. 551,795.

To all whom it may concern:

Be it known that I, THOMAS E. CARR, a citizen of the United States, residing at Providence, in the county of Providence and State of Rhode Island, have invented certain new and useful Improvements in Train Stops, of which the following is a specification.

This invention relates to means for automatically stopping trains if for any reason the engineer fails to observe the signals which are set against him, and the object of this invention is to provide simple, positive and effective means whereby it is impossible for a train to pass a signal that is set at stop position without having the steam shut off and the brakes applied.

A further object of the invention is the provision of means whereby the stopping mechanism will be actuated even if the engine is running backward along with the flow of traffic past a signal which is set against it.

A still further object of the invention is the provision of means whereby the tripper member which is connected to the signal will be automatically set at stop position, if for any reason the connection between it and the signal should be broken.

The invention further consists in the provision of a tripper-operated arm so constructed that it will yield upon engaging some object side of the track when the engine is running in a direction reverse to that in which the arm is designed to be operated by the tripper.

The invention still further consists in the provision of oppositely-operating, tripper-engaging arms located on opposite sides of an engine whereby the engagement of either side arm with the tripper member will cause the closing of the throttle and the applying of the brakes, one being designed to operate when the engine is running head first and the other when the engine is running backwards along with the flow of travel.

With these and other objects in view, the invention consists of certain novel features of construction, as will be more fully described, and particularly pointed out in the appended claims.

In the accompanying drawings:

Figure 1 is a rear end elevation of the engine showing my improved stop mechanism applied thereto.

Figure 2 is a plan view of the stop mechanism carried by the engine, a portion only of which is shown.

Figure 3 is a side elevation illustrating 60 the signal and its connection to the tripper mechanism.

Figure 4 is a plan view showing the mechanism by which the tripper-member is connected to the signal. 65

Figure 5 is an enlarged elevation of the tripper-member also showing a weighted pulley around which the chain is led for connecting this tripper to the signal.

Figure 6 is a view showing the tripper 70 and the weight for returning the tripper to operative position if its connection to the signal should be broken.

Figure 7 shows the tripper moved to inoperative position and the counter-balance 75 weight in position to return it to operative position.

Figure 8 is a top view of the tripper-engaging arm, its dotted position showing it moved out of normal by being engaged on 80 its rear side when the engine is moving in a direction opposite to that in which the arm is designed to operate.

Figure 9 is a side elevation of this tripper-engaging arm. 85

With reference to the drawings, 10 designates the signal post on which the usual semaphore or other signal 11 is pivotally mounted. To this semaphore I have applied a pulley 12 around which is wound an 90 operating cord or chain 13 which leads over the idler pulleys 14 and 15 to the tripper-operating pulley 16 which is mounted on the shaft 17, the latter being mounted in the bearing block 18, and on this shaft is also 95 mounted a tripper-member 19 which is mounted a tripper-member 19 which is adapted to be rotated in a plane parallel with the track, to be moved either into or out of operating position by a corresponding movement of the signal 11. By this construction when the signal is moved to stop position the tripper which is mounted adjacent the track, is moved into position to engage the automatic stopping mechanism on the engine, presently described, to stop the 100 engine and when the signal is moved to clear position this tripper is dropped out of operating position to permit the train to

105 pass undisturbed.

In order to cause the tripper-member 19 110 to be moved to operative position, if for any reason the chain 13 should be broken while

this tripper is in inoperative position, I have pivoted a counter-balance weight 20 to the pulley 16 on the pin 21 which when the tripper is moved to inoperative position, as illustrated in Figure 7, will lay against the pin 30 in position to rotate the pulley 16 and shaft 17 to move the tripper-member into upright position as illustrated in Figure 6, against the stop 22 ready to be engaged by the train-stopping mechanism even though its connecting chain to the signal be broken.

In applying my automatic train-stopping device to an engine I mount the upright shaft 23 in upper and lower bearings 24 on the rear of the cab, and to the lower end of this shaft I attach the tripper-engaging arm 25, which arm is mounted to swing on this shaft and a hub member 26 is fixed to the shaft and is provided with a stop-lip 27 against which the corresponding lip 28 of this arm is caused to abut being pressed back under tension of spring 31.

Another short shaft 35 is positioned near the forward end of the cab supported in upper and lower bearings 36, and on the lower end of this shaft is fixed an arm 37, which is connected to arm 34 on shaft 23 by connector 38. This engine is provided with the usual steam throttle, as indicated at 39, for shutting off the steam, which throttle is operated by the usual head-lever 40 pivoted at its outer end at 41 and to the throttle at 42, its free end 43 being provided with a handle to be engaged by the hand of the engineer, and this lever is provided with a latch 44 engaging spaced-apart notches in the quadrant 45 under tension of spring 46, and a latch-operating lever 47 is placed adjacent the handle whereby the grip of the engineer upon the handle also serves to withdraw the latch from its notch to permit the free movement of the throttle lever.

On this throttle lever I have mounted an auxiliary latch operating lever 48 which is pivoted at 49 on the throttle lever 40, its outer end being pivotally connected to the latch-rod 44, and in order to lift this latch from engagement with the notches in the quadrant I have provided a shoe 50 pivoted at 51 to the bracket 52, said shoe being provided with a lever arm 53 which is adapted to be operated by rotation of the short shaft 35 through the arm 54 and connection 55, whereby when the tripper 19 is engaged by arm 25 while the engine is wrongly moving past the same with the signal set against it, the action of this arm 25 through the mechanism above described causes the shoe 50 to press upon the auxiliary lever 48, withdraw the latch 47 from the quadrant and at the same time press the throttle-lever forward to shut off the steam from the engine and also at the same time the air-

brake operating lever 56 is manipulated to apply the brakes through the movement of lever 57 which also is mounted on shaft 35 and slotted connector 58. The slot 59 in this connector 58 permits the free movement of the brake-lever to apply the brakes independently of this stopping mechanism.

After this throttle-operating and brake-applying mechanism has performed its function by contact with tripper 19 it is automatically returned to normal by the spring 64 through lever 60, connector 63 and oscillating arm 61, which latter is pivoted at 62.

It is often found in practice desirable to run the engine backward along with the flow of traffic and under such conditions I have also found it desirable to provide means to prevent the engineer from running past a signal which is set against him, and to accomplish this in a simple and effective way, I have provided a duplicate tripper-engaging lever 65 on the opposite side of the engine, which is mounted on the shaft 66 to operate similarly to the arm 63 and this arm is connected to the oscillating arm 61 through the connector 67 and arm 68 and is assisted by spring 69 to return with the mechanism to normal after having operated the same.

By the use of my improved mechanism it will be seen that when the tripper device is set against the train it will operate mechanism on the engine to both shut off the steam and apply the brakes and to release both automatically after having been operated and to be again actuated by the engineer if desired, also by my improved mechanism the engineer is unable to run past a signal set against him even though the engine is running backward with the flow of traffic.

My improved device is simple and practical in construction and effective in its operation and by its use it is impossible for an engineer to run past a signal which is set against him without being promptly notified of the fact and the engine automatically stopped in case any accident should have happened to the engineer.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An engine control mechanism adapted to be operated in combination with a signal operated tripper comprising, a steam throttle control lever carried by the engine, a relatively stationary toothed segment, a lock latch for engaging said segment, a manually operable rod for withdrawing said latch

carried by said lever, an auxiliary lever directly connected at one end to said rod, an arm extending from said engine for engaging a signal operated tripper and means 5 operated by said arm to automatically operate said auxiliary lever and rod to withdraw said latch and move the throttle lever to stop position.

2. An engine control mechanism adapted 10 to be operated in combination with a signal operated tripper comprising, a steam throttle control lever carried by the engine, a relatively stationary toothed segment, a lock latch for engaging said segment, a manually operable rod for withdrawing 15 said latch carried by said lever, an auxiliary lever directly connected at one end to said rod, a shoe for directly engaging the other end of said auxiliary lever, an arm extending from said engine for engaging a signal 20 operated tripper and means operated by said arm to automatically throw the shoe to operate said auxiliary lever to withdraw said latch and move the throttle lever to 25 stop position, and spring actuated means for causing said shoe to release said throttle lever and auxiliary lever after moving the same to stop position.

3. An engine control mechanism adapted 30 to be operated in combination with a signal operated tripper comprising, an operating shaft, brake and throttle levers adapted to be engaged by means controlled by said shaft, a tripper engaging arm at one 35 side of the engine directly connected to said shaft, a rock lever centrally pivoted, an oppositely disposed tripper engaging arm at the other side of the engine connected at one end to the rock lever a link operatively con-

necting the other end of the rock lever to 40 the operating shaft whereby engagement of the trippers in opposite directions will cause like movement of the operating shaft to apply the brakes and shut off the throttle, and a spring acting on the rock lever to return the operating shaft to normal position after the same has been moved to final position.

4. A signal operated tripper for train stopping mechanism comprising a signal, a 45 cooperating tripper adapted to operate the stop mechanism on an engine, means for connecting said signal and tripper whereby a movement of said signal to danger position correspondingly moves said tripper to 50 operating position, said tripper comprising a pulley with a radially extending engaging arm and a weighted arm pivoted to the pulley at a point substantially diametrically opposite to said arm to automatically move 55 the tripper arm to operating position upon the breaking of a connection to the signal.

5. An engine control mechanism adapted to be operated in combination with a signal 60 operated tripper comprising, a tripper engaging arm, an upright operating shaft directly connected to said arm, a jack shaft, 65 a crank arm on adjacent ends of the said shafts, a link connecting said crank arms, steam throttle and airbrake control levers, and means for operatively connecting said jack shaft to said throttle and brake control levers whereby engagement of the tripper arm by an operating tripper will cause the 70 levers to be moved to stop position.

In testimony whereof I affix my signature.

THOMAS E. CARR.
